MECHANICAL PENCIL

Fred Ferber, Englewood, N. J.

Application July 3, 1947, Serial No. 758,935

5 Claims. (CL 120—17)

1

My invention is an improvement in mechanical pencils of the type having a magazine to carry a supply of leads of the proper length, and parts adapted to move each lead successively into position to protrude from the pencil, so that the latter can be employed for writing whenever the owner needs it for such a purpose.

An object of the invention is to provide a mechanical pencil of simple but superior design, comprising relatively few parts that can be easily and inexpensively produced and readily assembled, and capable of smooth and certain actuation; subjecting the leads to no breaking stresses and keeping them intact and unbroken and otherwise unimpaired as they are moved into place and caused to project at the tip of the pencil for their intended use.

A further object is to provide a mechanical pencil having a casing with a guiding tube for the leads, said tube being of novel form and mounted in a bearing member that permits reciprocating movement of the tube to feed the lead to the point of the pencil, and to return to its starting point; the tube and the bearing member being so shaped that they can be quickly joined but are afterwards virtually inseparable. This construction facilitates the proper union of the various parts and the maintenance of the unit in efficient serviceable condition is thus assured.

The drawings show the preferred embodiment of my invention and the characteristics are defined in the appended claims. But this disclosure is explanatory only; and I do not wish to be restricted to the exact structural details herein set forth. In practice I may resort to various minor alterations without deviating from the general principle which underlies the construction and mode of operation, or omitting any of the essential features wherein the invention resides.

On the drawings:

Figure 1 is a section through the casing and inner parts of a mechanical pencil in accordance with my invention.

Figure 2 is a similar view with the parts in different positions; and

Figure 3 is a separate view in section of the guide tube for the leads.

In the drawings, the numeral 1 indicates a cylindrical casing, having a removable conical tip 2 at the front end, this tip being attached to the casing and held in place by any suitable means. Within the tube is a movable sleeve 3 which projects from the other extremity (not shown) of the casing 1; and contains the leads 4. One of

these leads represented at 5 is shown in the middle of the casing projecting from the point of the tip 2. The sleeve 3 can be moved inward by pressing on its projecting end to push the central lead 5 so that its extremity protrudes from the tip, so that it can be utilized for writing.

The guiding tube for the central lead 5 is indicated at 6. One end has a collar or flange 7, this end having a concave surface 8, which is enveloped by the inner end of the sleeve 3. The bore 9 of the tube 6 is of sufficient size to receive one of the leads which are stored in the sleeve 3; and, because of the concave surface 8, one of the leads will always slip into line with the bore 9 and move into it. In the sides of the tube 3 are slots 10, through which project jaws 11, the function thereof being to grip the central lead 5 and move it towards the tip 2 in a manner explained below. At the end opposite the collar 7 the tube 6 has slots 12, opening through said end, and permitting said end to be transversely compressed to a slight extent. At the same end the bore 9 has inside teeth or serrations 13.

The tip 2 has a counterbored recess 14 at its inner end, internally threaded at 15 to engage and hold a hollow bearing member 16 in one piece, having a collar or flange 17. Integral with this member or gland 16, which has a central bore 18 through it, are two substantially semicircular lugs 19 projecting up from the collar 17. These lugs are separated from one another by small spaces between their opposing side edges, said spaces being of uniform width; and between the side edges the inner faces of the lugs are concave on the same radius as the bore 18, forming a continuation 20 thereof. The ends of the lugs 19 remote from the collar 17 have inside projections or rims 21 presenting interior shoulders 22. Along the opposite edges the rims are counterbored or bevelled as indicated at 23. The tube 6 has opposed shoulders 24 and 25 between the slots 10 and the end having the inside teeth 13. Between these shoulders the tube 6 is thinnest, and from the shoulder 25 to said end the tube is still thinner than between the slots 10 and collar 7. The extremity with the inside teeth 13 has the form of an expanded head 26 with a bevelled end 27. This head is thicker than the inside diameter of the bore 18 in the gland 16; but it can be forced between the counterbored rims 21 and through the bore 18; the part of the tube 6 with the slots 12 then yielding till the contractile head or end 26 projects from the threaded end of the gland 16. This gland 16 with the tube 6 is then inserted into the casing 1; the threaded

50 55

end of the gland projecting from the open end of the casing; and the tip 2 can then be screwed upon the gland 16.

When the gland 16 and the tube 6 are thus assembled, the internal rims 20 are between the shoulders 24 and 25, and with these shoulders and the shoulders 21 limit the movement of the tube 6. Adjacent the collar 7 and tube 6 is snugly encircled by a ring 28 to which the resilient jaws 11 are secured by their ends; and encircling the jaws 11 is a tubular slideable bushing 29 encircled by the adjacent end of the sleeve 3, and having a collar 30 between its ends abutting the inner extremity of said sleeve. The jaws project from the end of the bushing beyond the collar 30, and their outer edges 31 diverge from the axis of the casing 1. The inner surface of the bushing at the adjacent end 32 flares somewhat; so that, when the bushing 29 is pushed towards the tip 2, it squeezes the jaws 11 into gripping engagement with the lead 5 and feeds it towards the open end of the tip. Between the collar 30 and the collar 17 of the gland 16 a spring 33 encircles the bushing 29 and the lugs 19, and this spring normally holds the bushing 29 and collar 7 with the tube 6 in the positions shown in Figure 1. Then the lead is gripped by the enlarged end 26 of the tube 6, the toothed portions between the slots 12 constituting jaws like the jaws 11; because the tube 6 is pushed up by the spring 33 acting on the bushing 29, which engages the ring 28 and presses it against the collar 7 to draw the end 26 into the end of the gland 16; so that the teeth 13 bind the lead and hold it in readiness for writing. When the sleeve 3 and bushing 29 are actuated to move against the force of the spring 33, the ring 28 displaces the tube 6 in the gland 16 enough to release the jaws 13, because the ring 28 exerts enough friction on the tube 6 to move it slightly. Then the jaws 11 can feed the lead forward as required.

As stated above, the extremity of the sleeve 3 projects from the end of the casing opposite tip 3; and the lead 5 is fed forward merely by pressing on this end with the finger. In the bore of the tip 2 is a lining 34, with an enlarged inner end 35, snugly fitting an enlarged part of said bore adjacent the recess 14 in the tip 2. This lining has longitudinal slots 36 opening through the opposite extremity, and except for the part 35, it fits the bore of the tip loosely, so that it will grip the end of the lead 5 passing through it lightly, but yield sufficiently so that the lead will not be obstructed or retarded. It terminates within the tip 2, and the opening at the point of the tip is just large enough to pass the lead, bracing the lead all round its circumference and diminishing the risk of breaking it off.

The structure set out above thus makes both the tube 6 and gland 16 a one-piece unit, no part of which can get out of operative position. If

the tube consisted of two or more parts threaded to be screwed together, it would be weak and the parts could not be properly lined up. The lead would break, or part of the tube would become separated from the remainder thereof. As illustrated and described, this tube is straight, strong, rigid, and durable. The pencil is also easy and quick to assemble, as above stated; because to connect the tube 6 and the gland 16, the end 26 of the tube is merely thrust past the chamfered edges 23. The length of the feed of the lead is nicely determined and limited; so that too much of the lead does not stick out from the tip and loss by breaking off of the lead is avoided.

Having described my invention, what I believe to be new is:

1. A pencil having a casing, a bearing member with a bore through it in said casing, said member having lugs with opposed internal projections, a guide tube in said bore, said guide tube having opposed external shoulders and being relatively thin between said shoulders, said projections being between said shoulders.

2. The pencil according to claim 1, in which the space between the lugs is substantially equal to the diameter of the bore, and the tube has a contractile end thicker than said diameter.

3. The pencil according to claim 1, in which the space between the lugs is substantially equal to the diameter of the bore, and the tube has a contractile end thicker than said diameter, said tube and said member each being in one piece.

4. A pencil having a casing, a bearing with a bore through it in the casing, said bearing having opposed lugs at one end, said lugs having concave inner surfaces spaced apart by a distance substantially equal to the diameter of the bore, said lugs having opposed internal rims presenting shoulders, a guide tube in said member, said tube having shoulders and a relatively thin part between said shoulders, said rims being between shoulders, and the tube having an enlarged slotted head adjacent the opposite end of the bearing.

5. The pencil according to claim 4 in which the bearing member and the tube are each in one piece, and the tube is slotted from the head to the shoulder at the remote end of said thin portion.

FRED FERBER.
